(57) **CLAIM**

The ornamental design for a handheld multi-tool with opposing roller and cutting blade, as shown and described.

DESCRIPTION

FIG. 1 is a front, side perspective view of a handheld multi-tool with opposing roller and cutting blade showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken lines depict portions of the multi-tool with opposing roller and cutting blade in which the design is embodied that are not considered part of the claimed design.
